SURGICAL TABLE

Maurice Georges Heitz-Boyer, Vichy, France; vested in the Attorney General of the United States

Application September 5, 1942, Serial No. 457,509
In France June 5, 1941

3 Claims. (Cl. 250—55)

1

My invention relates to adjustable tables such as those for surgical purposes, those used as drawing boards, etc. and it refers more particularly to tables for surgeons operating with the aid of X-rays.

My invention has for its object to provide a table of the kind above-referred to which will be more easily adjustable and thus more convenient in use than the known tables.

It is a further object of the invention to provide a table for surgical and the like purposes for use with an X-ray tube device, in which the table has a single supporting column carrying a substantially flat track on which is movably mounted a body support for cycloidal movement on the track. On the under side of the body support there is movably carried a support for the X-ray tube device, and the mounting of the body support on the column for cycloidal movement on the track is positioned and dimensioned to prevent contact of the X-ray tube device with the column.

In the annexed drawings:

Fig. 1 is a perspective view with parts in section showing a table constructed in accordance with my invention.

Figs. 2 and 3 are side and end views thereof, some parts being shown in section in Fig. 3, the plane of section being indicated at III—III in Fig. 2.

Figs. 4 and 5 are also side and end views with parts in section, showing the table at another position of the parts.

Fig. 6 is a diagram illustrating the movement of the main parts when the table is oscillated about its transverse axis.

Figs. 7, 8 and 9 refer to the electrical equipment of the table which is shown in end view, plan view and partial view to an enlarged scale, respectively.

Fig. 10 is a perspective view showing a lateral abutment.

Fig. 11 shows the stretcher, the "arching device" and the shafts which may be associated therewith.

Figs. 12 and 13 are respectively a perspective view and a plan view of an X-ray bulb support adapted to be associated with the table.

The table shown in the drawings comprises a base 1 supported by means of castor wheels, the said base being provided with a telescopic column 2 associated with a gearing to operate same in order to vary its height.

The table proper 3 is supported by column 2 through a mechanism adapted to permit its ad-

justment about a transverse axis, such mechanism comprising a pair of horizontal racks 4 and 4g fixed to side members 5d and 5g connected by a transverse member 5, and a pair of toothed sectors 6 and 6g cooperating with said racks. Members 5, 5d and 5g form a rigid structure fixed to column 2, while sectors 6 and 6g are rigidly carried by the longitudinal members 7d and 7g of a frame 7 which carries the table proper 3, as it will be explained below.

Carriages 8 and 8g are adapted to slide longitudinally along the upper part of side members 5d and 5g and they are actuated by a pair of longitudinal screws 9 and 9g horizontally and pivotally carried by the end portions 5t and 5p of members 5d and 5g. They are provided with trunnions on which sectors 6 and 6g are pivoted.

Fig. 6 clearly demonstrates the operation of the gearing described.

When screws 9 and 9g are actuated in unison (which is obtained by any appropriate means, such as chains and sprockets) carriages 8 and 8g are moved longitudinally and sectors 6 and 6g are oscillated together with frame 7 to which they are rigidly fixed. The assembly comprising the X-ray bulb and associated parts, carried by frame 7, thus assumes positions such as shown at 10A, 10B and 10C and is tangent to a cylindrical geometrical surface XY, the section of which is a cycloid. It will easily be grasped that this is an advantage with respect to the mere pivoting of frame 7 about a fixed transverse axis, as is the known constructions; more particularly my invention provides ample space for the X-ray bulb for any position of the table and avoids any risk of breakage of the same against the supporting column 2.

Frame 7 supports two columns 11 and 11p respectively fixed to its rear and front transverse members 7t and 7p, said columns pivotally carrying the rear and front transverse members 3t and 3p of the frame 3 forming the table proper. Two rods 12 and 12p are articulated at their upper ends to one of the ends of members 3t and 3p while their lower ends are pivotally connected with carriages 13 and 13p forming nuts on transverse screws 14 and 14p respectively. It will be understood that by operating screws 14 and 14p in unison by appropriate means, table 3 may be pivoted at will about a longitudinal axis.

As shown in Figs. 7 to 9, column 2 may be operated by an electric motor 15 housed within base 1, this motor being electrically connected through a plug 15⁰ (Fig. 3) with a pair of pedals 15¹ and 15² (Fig. 1) disposed on a separate base

or switchboard 16 and corresponding to upward and downward movement of column 2. There is also provided a switch with an operating head 15¹⁰ connected by a chain 15²⁰ with member 5 and adapted to be actuated when the table reaches respectively its lowermost and its uppermost positions to cause stoppage of motor 15 while permitting its rotation in the reverse direction.

The mechanical connection between motor 15 and column 2 comprises a clutch 20 and a shaft with a square and 15⁰⁰ projecting from the gear case and adapted to receive an actuating handle, in order to permit hand actuation when the motor is de-clutched.

A second electric motor 17 is provided to actuate screws 9 and 9g; it is energized through a plug 17⁰ to which it is connected by means of wires passed through an articulated tubing 18. Plug 17⁰ is itself connected with pedals 17¹ and 17² on base 16. And there is also provided a pair of end switches 17¹⁰ and 17²⁰ to cause motor stoppage at the ends of the stroke.

In Fig. 7 it will be seen that motor 17 drives a shaft 17d extending horizontally along one side of the structure, said shaft being chain connected with another shaft 17g extending along the other side, and shafts 17d and 17g driving screws 9 and 9g by means of chains and sprockets. Hand actuation is enabled by a square end 17⁰⁰ in cooperation with a clutch not illustrated.

A third electric motor 19 is disposed within a casing 19⁰ on member 7d of frame 7; it is controlled through a plug 19⁰ by pedals 19¹ and 19² on base 16, associated with end switches 19¹⁰ and 19²⁰. The gearing between motor 19 and screws 14 and 14p comprises a pair of gears connecting said screws with an actuating shaft 14d carried along member 7d. Shaft 14d is connected with motor 19 by means of a slidable pinion 19³ forming a clutch and there is provided a square 19⁰⁰ to permit hand actuation.

The support 10 of the X-ray bulb is slidably fixed on the transverse sides 20 and 20t of a frame, the longitudinal sides 20d and 20g of which are slidable along members 7d and 7g. The side member 20g is provided with two superimposed longitudinal bores; the first one, which is threaded, is adapted to receive a screw 21 pivotally supported by frame 7; and the second one which is cylindrical, slidably receives a square shaft 22 also pivotally carried by frame 7. There is provided a chain sprocket 22g on shaft 22 and another chain sprocket 22d loose on a journal carried by the other longitudinal side 20d, and sprockets 22g and 22d are connected with each other by means of a chain fixed to a pin 10⁰ carried by the corresponding transverse side of support 10.

It will be understood that the X-ray bulb may thus be moved longitudinally by actuating screw 21, and transversely by actuating shaft 22. This actuation may be performed by hand, through square ends 21⁰ and 22⁰, or electrically, by means of an additional frame freely carried by the means of the kind described with reference to Figs. 7 to 9.

The arching device comprises a pair of rectangular plates 23 articulated to each other along one of their transverse sides while their opposed transverse sides are provided with wings 24 with transverse pins. This device also embodies two pairs of slides 25, which are mounted respectively on the right and left transverse members of frame 3 or, preferably as shown, on the transverse mem-

bers 26d and 26g of an additional frame freely carried by the former and adapted to be used as a stretcher for carrying the patient, by means of sockets 26 provided in the angles of the said additional frame to receive gudgeons 27 projecting upwardly from the carrier shafts 27d and 27g (Fig. 11). Slides 25 are provided with inwardly projecting edges having on their upper face a series of notches adapted to receive the transverse pins 10 of wings 24 respectively.

Means are also provided to move the slides of each pair towards those of the other pair, such means comprising preferably a pair of screws 28d and 28g pivotally carried by the additional frame 26 in parallel relation with respect to the longitudinal members thereof, such screws being provided with opposed pitches in such a manner that by rotating same the two pairs of slides may be moved in opposed direction. Screws 28d and 28g are driven either by hand, through a square end 29, or electrically by means such as described with reference to Figs. 7 to 9.

The table described also comprises a head support 29 and a foot support 29p, each being carried by broaches driven through the tubular ends of the longitudinal members of frame 3 and fixed at the appropriate position by means such as radial pins.

Fig. 10 shows an adjustable abutment comprising a split collar 30 slidably keyed on transverse member 3g (or 3d) and clamped in position by means of a screw 30¹, a double plain collar 31 formed of two elements between which collar 30 is positioned, and a body 31¹ integral with collar 31, the said body receiving the lower end of a tubular rod 32 forming a telescopic arrangement with another 33. The upper end of rod 32 is split and it is provided with a clamping screw 32¹. Rod 22 carries a split collar in which there may be clamped a rod 34 to which there is articulated the curved plate 35 forming the abutment proper. A screw 33¹ permits of clamping rod 34 at the desired position.

Collar 31 is angularly fixed on member 3g by means of ratchet teeth cut in collar 30 and engaged by a pawl, not illustrated, pressed by a spring and freed by a hand lever 31². It will readily be grasped that by lifting lever 31² the pawl is disengaged from the ratchet and collar 30 is free to rotate.

There is associated with the table described an X-ray support comprising a carriage 36 supported by castor wheels and provided with broaches 37 and 37g by means of which it may be fixed to the base 1 of the table through sockets (not shown) provided on the same. This carriage supports two uprights 39d and 39g connected by a cross-bar 39. Uprights 39d and 39g slidably support sleeves 40 and 40g, each carrying another sleeve 41 and 41g respectively, with their axes horizontal. Arms 42 and 42g are driven through sleeves 41 and 41g; they are preferably square in cross-section, as well as the corresponding sleeves themselves, and they are provided with a circular axial hole. Each arm supports a rod 43 and 43g engaged into the axial bore thereof and having at its rear end a clamping device comprising a handle 44 or 44g adapted to be screwed on the said end. Arms 42g and 42 support a frame 46 adapted to receive a screen or a photographic plate and an X-ray bulb 47.

Pulleys 48d and 48g are arranged at the upper 75 end of uprights 39d and 39g on the same trans-

verse shaft 48. The lower end of said uprights also comprises pulleys 49g and 49 and the said pulleys receive two endless wires or strings 49g' and 49d attached to noses 50 and 50g carried by sleeves 40 and 40g. Counterweights 51 and 51g are provided to balance the weight of the parts associated with the sleeves.

The carriage also supports the electrical apparatus 52 supplying current to the X-ray bulb, and it is provided with a column 53 with an articulated handle 54 by means of which the carriage may be moved.

It will easily be grasped that the carriage thus established permits of placing the X-ray bulb and the corresponding frame at any position. Fig. 13 shows by way of example in dash and dot lines the position corresponding to an X-ray exposure with the bulb under the body.

I claim:

1. A table for surgical and like purposes for use with an X-ray tube device, which comprises, in combination, a single supporting column, a substantially flat track carried by the top of said column, a body support, means movably carried by said body support on the under side thereof for supporting an X-ray tube device, and means for movably mounting said body support on said column for cycloidal movement on said track, said last mentioned means being so positioned and dimensioned as to prevent contact of said X-ray tube device with said column.

2. A table for surgical and like purposes for use with an X-ray tube device, which comprises, in combination, a single supporting column, a substantially flat track carried by the top of said column, a body support, means movably carried by said body support on the under side thereof for supporting an X-ray tube device, and means for movably mounting said body support on said column including arcuate members in rolling engagement with said track, said members being so positioned and dimensioned with respect to

said X-ray tube device as to prevent contact thereof with said column.

3. A table for surgical and like purposes for use with an X-ray tube device, which comprises, in combination, a single supporting column, at least two parallel horizontal racks carried by the top of said column, a body support, means movably carried by said body support on the under side thereof for supporting an X-ray tube device, at least two sector gears depending with said body support and in mesh with said racks respectively, said sector gears being movable about a common axis and having their gear teeth so positioned with respect to said X-ray tube device as to prevent contact thereof with said column, and means for causing rolling movement of said sector gears along said racks.

MAURICE GEORGES HEITZ-BOYER.
